CLAIM

The ornamental design for a television receiver, substantially as shown and described.

DESCRIPTION

FIG. 1 is a front perspective view of a television receiver showing our new design;

FIG. 2 is a right side elevational view;

FIG. 3 is a top plan view; and

FIG. 4 is a rear elevation view.

The left side is a mirror image of the right side.

*Fig.1.**Fig.2.**Fig. 3.**Fig. 4.*
